Patented Jan. 2, 1973

225,718

LIQUID SPRAY DISPENSER

John F. Gorman, 3207 Fryman Road,
Studio City, Calif. 91604

Continuation of abandoned design applications Ser. No.
18,062, and Ser. No. 18,063, both July 7, 1969. This
application Feb. 16, 1970, Ser. No. 21,456

Term of patent 14 years

Int. Cl. D9—01

U.S. Cl. D9—8

FIG. 1.

FIG. 2.

FIG. 3.

FIG. 4.

FIG. 5.

FIG. 6.

FIG. 8.

FIG. 9.

FIG. 10.

FIG. 11.

FIG. 12.

FIG. 13.

FIG. 1 is a rear perspective view of a liquid spray dispenser showing my new design in closed position;

FIG. 2 is a rear elevation thereof;

FIG. 3 is a front elevation thereof;

FIG. 4 is an elevation of the side opposite that shown in FIG. 1;

FIG. 5 is a top view;

FIG. 6 is a bottom view;

FIG. 7 is a front perspective view thereof in open position;

FIG. 8 is a front elevation of the open dispenser;

FIG. 9 is a rear elevation of the open dispenser;

FIG. 10 is an elevation of the side opposite that shown in FIG. 7;

FIG. 11 is a top view of the open dispenser;

FIG. 12 is a bottom view of the open dispenser; and

FIG. 13 is a fragmentary section, taken on line 13-13 of FIG. 7.

This is a continuation of design applications Ser. No. D. 18,062 filed July 7, 1969 and Ser. No. D. 18,063 filed July 7, 1969, both now abandoned.

I claim:

The ornamental design for a liquid spray dispenser, as shown and described.
